UNITED STATES PATENT OFFICE.

WILLIAM J. WALTERS, OF PROSPECT, NEW YORK.

CUFF-HOLDER.

SPECIFICATION forming part of Letters Patent No. 376,457, dated January 17, 1883.

Application filed June 3, 1887. Serial No. 240,143. (No model.)

To all whom it may concern:

Be it known that I, WILLIAM J. WALTERS, of Prospect, in the county of Oneida and State of New York, have invented a new and useful 5 Improvement in Cuff-Holders, of which the following is a full, clear, and exact description.

My invention relates to an improvement in cuff-holders, and has for its object to provide 10 a device quickly and conveniently applied to a cuff, whereby the same may be securely held in position upon the wrist, and which holder may be simply and cheaply constructed, and is of neat appearance.

15 The invention consists in the construction and combination of the several parts, as will be hereinafter fully set forth, and pointed out in the claims.

Reference is to be had to the accompanying 20 drawings, forming a part of this specification, in which similar letters of reference indicate corresponding parts in all the figures.

Figure 1 is a plan view of the complete device, illustrating its application to a cuff, and 25 Fig. 2 is an edge view of the holder. Fig. 3 is a plan view of the holder unattached, and Fig. 4 is a front elevation of the same.

In carrying out the invention the holder is 30 preferably made in three integral parts—namely, the head A', the shank B, and the tie B'. The tie B' is adapted for attachment to the piece of elastic C, or other suitable or equivalent material, carrying at one end any approved form of a spring-snap, D, for attachment 35 to a shirt. The tie B' consists of aligning-wings b, projecting from each side the shank at right angles thereto, and a pointed tongue, b', in the same plane with said shank, extending rearward integral with the inner central 40 edges of the aforesaid wings, as shown in Fig. 3.

The shank B is made straight at its intersection with the tie, but as it projects forward to a connection with the head A', an edge view of the shank would present a wave-line, where- 45 by it is formed with the upper surface depression, d, and convexity d'. Where the shank joins the head it again assumes a straight line, as shown in Figs. 2 and 3.

The head A' and the shank form more or 50 less the letter T, the said head extending outward upon each side at right angles to the shank, terminating at the extremities in rearwardly and inwardly projecting semi-spherical tabs a. Between the inner edges of said

tabs and the outer edges of the shank U-shaped 55 spaces a' are provided, as seen in Fig. 3. The head A', at each side the shank, is bent outwardly and down to form the irregular depression a'', and the said tabs are thereby raised above the plane of the central portion of the 60 head, and also above the plane of the shank.

In attaching the holder to an elastic strip, C, or a strip of any pliable material carrying a clip, D, as aforesaid, the tongue b' is inserted 65 in the strip centrally near one edge and bent over upon itself and upon the under face of the strip, as shown in Figs. 1 and 4, the wings being bent over upon themselves to clamp or bind transversely the sides of the strip.

When inserting the holder in the button-hole of a cuff, one tab a is preferably entered 70 first, and then the next. Both tabs being entered, the shank and tie at their junction lie flatly upon the inner side of the cuff, and the outer or upper portion of the shank flatly upon 75 the outside of the cuff, while the tabs are at a slight elevation above the same at their outer ends. When the device is, however, pulled down to its proper position, the tabs pass over the projecting lower edge of the button-hole 80 and rest upon the surface of the cuff surrounding said hole, the lower edge of the same near each end coming in contact with the upper wall of the U-shaped spaces a', or the inner 85 edge of the head, as shown in Fig. 1.

Having thus described my invention, what I claim as new, and desire to secure by Letters Patent, is—

1. A holder for cuffs, constructed in one piece, consisting of the head A', provided with 90 inwardly and upwardly projecting tabs a, the shank B, slightly concavo-convex near the center, and the tie B', connected with said head by the shank, substantially as herein set forth.

2. A holder for cuffs, constructed of one 95 piece, consisting of the head A', provided with inwardly and upwardly projecting tabs a and recesses a', the shank B, having a concavity, d, and convexity d' near the center, and a tie, B, whereby the holder is attached to the strip 100 C, consisting of the wings b, and pointed tongue b', all arranged substantially as herein shown and described.

WILLIAM J. WALTERS.
